RECORDING THERMOMETER CONTAINER
Arthur R. Taylor, Bellevue, Wash., assignor to Ryan Recording Thermometer Co., Seattle, Wash., a corporation of Delaware

Filed June 12, 1964, Ser. No. 374,598
2 Claims. (Cl. 220—57)

The present invention relates to a waterproof container for housing a recording thermometer and is of the general type shown in U.S. Patent No. 2,772,016. It is contemplated that the recording thermometers for which the present invention is designed will be of the bi-metallic coil sensing type with clock wind described, for example, in U.S. Patents Nos. 1,989,856 and 3,119,269.

Recording thermometers have found important application in hydrographical monitoring requiring that the instruments be submerged. In such cases, even though the instruments are frequently suspended within perforated tubes for protection, they are commonly subjected to aquatic jostling. This motion endangers seals and makes O-rings, if used, susceptible to a pumping action resulting in the pulling of water into the container. Accordingly, the present invention aims to provide an improved container for recording thermometers which is waterproof when submerged, even under adverse conditions, and yet is of simple and economical construction, and can be readily opened and reused without application of sealing compounds or adhesives.

Other more particular objects and advantages of the invention, will, with the foregoing, appear and be understood in the course of the following description and claims, the invention consisting in the novel construction and in the adaptation and combination of parts herein-after described and claimed.

In the accompanying drawing:

FIG. 1 is a perspective view of a container embodying the present invention.

FIG. 2 is a vertical sectional view taken along the lines 2—2 of FIG. 1; and

FIG. 3 is a top plan view of the container.

Referring to the drawings it is seen that the container has a generally cylindrical casing 10 closed at the bottom and having a disc-like cover as a closure at the top. Starting at its base the container has a uniform diameter through the major part of its length and then the container wall slopes outwardly at 12 to a relatively short enlarged intermediate section 13. At the upper end of the latter the container again slopes outwardly by a shoulder 14 to a terminal rim section 15.

The cover 11 mates with the intermediate casing section 13 for sliding entry therein and is circumferentially grooved at 16 to receive an elastic O-ring 17 having a thickness somewhat greater than the depth of the groove so as to be susceptible to compression by the container wall section 13 and thereby act as a moisture seal. An annular recess 18 is formed on top of the cover and has a circumferential under-cutting groove 18a for receiving convenient tools for pulling the cover free of the container during disassembly to obtain access to the data compiled by the recording thermometer. At the center of the cover the base of the recess 18 is formed with a detent 18b to receive the free end of a clamping screw 22 in a manner to be hereinafter described. Secured to the base of the cover by screws 19 is an inverted cup-like adapter 20 into which is fitted the body 21 of the recording thermometer, the latter being outlined by broken lines in FIG. 2.

The casing 10, cover 11, and adapter 20 are preferably made of a non-corrosive material having high thermal conductivity such as aluminum so that the thermostatic elements of the recording thermometer will be accurately

2

subjected to temperature changes within the surrounding environment.

The rim section 15 of the container is horizontally slotted adjacent its lower end at diametrically opposite positions such as at slots 23—23. Adapted to extend through these slots are a pair of oppositely extending feet 24—24 formed at the bottom of the legs 25 of a yoke 26. The head 27 of the yoke has a threaded central opening 28 which receives the clamping screw 22. An eye 30 serves as the head of the screw and a lock washer 31 is provided between the eye and the yoke head 27.

Near their outer ends the yoke feet 24 are pierced to present respective openings 32 for receiving a wire keeper 33 bent in a generally semi-circular loop and having a relaxed diameter slightly exceeding the center-to-center distance between the openings 32. At the ends of this loop the keeper is formed with upwardly extending locking fingers 35—36 which bend inwardly toward one another at respective elbows 35a—36a. From its root end 20 the locking finger 35 slopes outwardly to its elbow 35a so that when the keeper is in locking position the elbow 35a slightly overlies the outer end of the respective foot 34 and the tip of the finger 35 overlies the inner edge of the respective opening 32 while the tip of the other finger 36 overlies the upper rim of the container. Since the diameter of the loop portion of the keeper exceeds that of the container sections 13 and 15 the plane of the loop normally is tilted downwardly about thirty degrees from the horizontal.

30 The keeper is unlocked by manually pressing downwardly on the keeper adjacent the finger 35 with the keeper lifted to the horizontal. This pressure forces the elbow 35a downwardly through the respective opening 32 while the tip of the finger 35 rides against the rim section 15 of the container, there being sufficient spring action in the finger to permit the necessary finger deflection for release. Then the keeper is swung about a quarter turn to swing the tip of the finger 36 free of the upper rim of the container whereupon it can be lowered 40 out of the respective opening 32 while at the same time gradually upwardly cocking the other end of the keeper. The keeper is applied by reversing the above releasing procedure.

To prepare for use, after the thermometer body 21 is 45 fitted into the adapter 20, it is lowered into the casing 10 and downward pressure is manually applied to upper face of the cover 11 to force the same to the level of the bottom edges of the slots 23. This causes a compression of the O-ring 17 between the floor of the cover groove 50 16 and the intermediate container section 13 to provide a cover seal. It will be noted that the upper shoulder 14 of the casing helps to guide the cover from the enlarged rim section 15 into the intermediate section 13 as the cover is pressed down. The yoke 26 is then applied by 55 first completely inserting one of its feet 24 in one of the slots 23 with the opposite end of the yoke cocked upwardly, then shifting the yoke to insert the other foot 24 after lowering the latter to the level of the slots. Following this the screw 22 is tightened to seat its lower end 60 against the floor of the detent 18b and force the cover 11 firmly against the shoulder 12 of the casing 10. Then the keeper 33 may be applied as previously described.

In hydrographic use the resulting unit may be conveniently lowered into the water to the desired depth 65 by playing out a line attached to the eye 30. The O-ring 17 maintains a watertight seal for the cover 11 and is prevented from moving relative to the casing 10 by way of the fact that the cover is firmly clamped against the shoulder 12 by the screw 22.

70 It is thought that the invention will have been clearly understood from the foregoing detailed description. Changes in the details of construction will suggest them-

selves and may be resorted to without departing from the spirit of the invention, wherefore it is my intention that no limitations be implied and that the hereto annexed claims be given a scope fully commensurate with the broadest interpretation to which the employed language admits.

I claim:

1. A container comprising, a generally cylindrical casing open at the top and having an enlarged upper rim portion terminating at its lower end at an inner annular stop shoulder, said rim portion having a pair of coplanar diametrically opposite slots spaced above said shoulder, and extending through said casing, a removable disc-like cover for said casing adapted to occupy a casing closing position beneath the level of said slots and seated against said shoulder, said cover having a circumferential groove formed in its outer edge, an elastic O-ring retained in said groove for sealing between said cover and said rim portion, a yoke having a pair of oppositely extending feet projecting radially 10 15 20

through said slots beyond said casing and each having a respective opening outside of the casing, keeper means extending through said openings, and a screw threaded through the center of said yoke and engaging the top of said cover.

2. The container of claim 1 in which the head of said screw has an eye.
